UNITED STATES PATENT OFFICE.

WILLIAM J. BREWER, OF BOMBAY, INDIA.

PULLEY-BLOCK.

SPECIFICATION forming part of Letters Patent No. 268,455, dated December 5, 1882.

Application filed March 22, 1882. (No model.) Patented in India April 10, 1880, No. 27; in England April 17, 1880, No. 1,588; in France October 18, 1880, No. 139,214; in Belgium October 18, 1880, No. 52,796, and in Austria October 29, 1881, No. 26,478.

To all whom it may concern:

Be it known that I, WILLIAM JOHN BREWER, a subject of the Empress of India, residing at Bombay, India, have invented a new and useful Improvement in Tackle-Blocks, of which the following is a specification.

This invention is part of my improvements in apparatus for reducing friction of axles, &c., patented in Great Britain by Letters Patent No. 1,588, dated April 17, 1880.

My present invention consists in an improved construction of tackle-blocks or pulley-blocks for hoisting-tackle, having reference to the employment or use therein of what I term "rotary lever-wheels," hereinafter termed "lever-wheels," for reducing friction and distributing strain and wear without complication of parts and without unnecessary weight or bulk.

Figure 1 of the accompanying drawings is a side elevation of an improved anti-friction tackle-block illustrating this invention. Fig. 2 is an edge view of the same, partly in section on the line 2-2, Fig. 1; and Fig. 3 is a like sectional edge view of another tackle-block embodying substantially the same invention.

Like letters of reference indicate corresponding parts in all the figures.

The improved tackle-block illustrated by Figs. 1 and 2 has a pair of flat cheek-plates, *a a*, of suitable size and outline, united solidly at top and bottom by a pair of rivets, *b c*, which support said plates at a given distance apart and parallel with each other, and serve respectively in the example to attach a suspending-clevis, *d*, and a depending hook, *e*. A pair of supplemental strain-bearing straps, *f f*, are likewise united by the same upper rivet, *b*, and depend therefrom outside of the cheek-plates *a*, being spread apart at about mid-length, and their parallel lower ends supported at a given distance from said cheek-plates by angle-braces *g*, Fig. 2, which in the example are of L shape in cross-section, being attached to the inner surfaces of said straps by welding. Extending downward from immediately below the offsets formed or supported by the angle-braces *g*, vertical slots are

cut in the cheek-plates *a* and straps *f*, to receive or accommodate the spindle ends or trunnions *h h*, belonging to a single grooved pulley, *P*, and those *i* belonging to a pair of rotary lever-wheels, *L L*. A pulley and pair of lever-wheels are inserted before the parts are united by the rivets *b c*, and in the finished block the peripheries of the rotary lever-wheels move in unison with, and thus form substantially frictionless bearings for, said spindle ends or trunnions *h* of the pulley *P*, said lever-wheels being adapted, owing to the reduced speed and correspondingly-reduced power at their spindles or trunnions *i*, to reduce and overcome frictional resistance at these points. To this end it is obviously important that each lever-wheel be equally supported on both sides, so as to run truly and without unequal strain, and this is accomplished without complication of parts and in a very light and compact block by the combination of the said slotted straps and their braces with the said slotted cheek-plates.

The tackle-block illustrated by Fig. 3 has parallel slotted cheek-plates *a² a²*, rivets *b² c²*, a clevis, *d²*, a hook, *e²*, slotted straps *f² f²*, with angle-braces *g²*, pulley-spindle ends or trunnions *h²*, and lever-wheels *L² L²*, with spindles or trunnions *i²*, which are similar to the parts correspondingly lettered in Figs. 1 and 2, save that the straps *f² f²* are extended downward and bent inward below the lever-wheels *L²*, and united to each other and to the cheek-plates *a²* by the lower rivet, *e²*, so as to render the structure stronger. Otherwise this block differs from the one first described in having two pulleys, *P¹ P²*, in place of the single pulley *P*. Other styles of tackle-blocks may be constructed according to this invention in like manner.

My improved tackle-block frame is adapted to be made wholly of a suitable metal or metals—iron and steel, for example. I do not, however, claim this *per se*. Neither do I claim broadly supporting the spindle or trunnions of the pulley or pulleys in the direction of strain by what I have termed "lever-wheels;" but

I claim—

In a tackle-block having a pair of rotary le-

ver-wheels to support the spindle or trunnions of its pulley or pulleys in the direction of strain, the combination, as hereinbefore specified, of a pair of slotted cheek-plates and a pair of supplemental strain - bearing straps, united with each other and with the suspension attachment at the upper end of the block, the lower ends of said straps being spread apart

and supported by angle-braces, so as to depend parallel to said cheek-plates, substantially to as shown, for the purpose set forth.

London, 23d January, 1882.

WILLIAM JOHN BREWER.
